UNITED STATES PATENT OFFICE

104,613

DESIGN FOR AN ELECTROTHERAPEUTIC APPARATUS CABINET

Arthur C. Haggstrom, Rockford, Ill., assignor to
The Burdick Corporation, Milton, Wis., a corporation of Delaware

Application April 12, 1937, Serial No. 68,679

Term of patent 7 years

To all whom it may concern:

Be it known that I, Arthur C. Haggstrom, a citizen of the United States, residing at Rockford, in the county of Winnebago and State of Illinois, have invented a new, original, and ornamental Design for an Electro-Therapeutic Apparatus Cabinet, of which the following is a specification, reference being had to the accompanying drawing, forming part thereof.

The figure is a perspective frontal view of the electro-therapeutic apparatus cabinet embodying my new design. The right side of the cabinet is essentially the same as the left side shown.

I claim:

The ornamental design for an electro-therapeutic apparatus cabinet as shown and described.

ARTHUR C. HAGGSTROM.
